(57) **CLAIM**

The ornamental design for a cable clamp, as shown and described.

DESCRIPTION

FIG. 1 is a top front perspective view of a cable clamp; FIG. 2 is a top elevation view thereof, with the bottom elevation view being a mirror image thereof; FIG. 3 is a front elevation view thereof; FIG. 4 is a rear elevation view thereof; FIG. 5 is a right side elevation view thereof; and, FIG. 6 is a left side elevation view thereof. The broken lines shown in the drawings depict weight reducing openings and a cable that form no part of the claimed invention.
